GOLF PUTTER HEAD

Lorin R. Todd, Burlingame, Calif.

Application March 13, 1959, Serial No. 54,989

Term of patent 14 years

(Cl. D34—5)

Fig. 1 is a rear view of a golf putter head embodying my new design;

Fig. 2 is a front view of the same;

Fig. 3 is a perspective view of the same;

Fig. 4 is a sectional view taken on the line 4—4 of Fig. 1;

Fig. 5 is an end view of the same, as viewed in the direction of the arrow in Fig. 2;

Fig. 6 is a top plan view of the same; and

Fig. 7 is a bottom view of the same.

I claim:

The ornamental design for a golf putter head, substantially as shown.
